UNITED STATES PATENT OFFICE.

STANLEY W. HAYES, OF RICHMOND, INDIANA.

TARGET-STAND.

Specification of Letters Patent.

Patented June 6, 1916.

1,185,662.

Application filed July 24, 1914. Serial No. 852,832.

To all whom it may concern:

Be it known that I, STANLEY W. HAYES, a citizen of the United States, residing in Richmond, in the county of Wayne and State of Indiana, have invented the following described new and useful Improvements in Target-Stands.

The invention is a target stand of few and simple parts, so combined and arranged as to be economically produced and protected in operation against interference by ice, stones or other foreign material, and also to be capable of operation with a minimum of frictional resistance.

In the accompanying drawing, Figure 1 is a vertical elevation of such a target stand; Fig. 2 is a top plan thereof; Fig. 3 a side elevation, with the staff broken off; Fig. 4 a horizontal section just above the crank arm; Fig. 5 a bottom plan of the base; Fig. 6 a vertical section in a radial plane; and Fig. 7 a vertical section through the lateral opening of the protecting chamber.

The base of the target stand is a fan-shaped casting 1, with spike-holes arranged along its longer or wider end 2, and the bearings for the target staff at its smaller or pointed end 3, the spike-holes being separated sufficiently from each other to provide a stable support upon the tie or roadbed. On its under side the base is reinforced by a series of ribs 4 (Fig. 5), which converge from the spike-holes toward the pointed end, and also by a marginal flange 5, the spike-holes being formed in the relatively thickened junctions between the ribs and the flange. At its smaller or pointed end the casting is provided with an upstanding wall portion 6, of general semi-circular sectional shape, and a series of angle-ribs 7 on the upper side of the casting serve to brace and strengthen this portion. These angle-ribs also converge toward the smaller end of the casting or the axis of the target staff.

The wall portion 6 in the present instance is disposed entirely above the general plane of the base-plate but this is not essential. The wall portion 6 forms a chamber, the roof of which is dome-shaped, as indicated at 8, and provided with an aperture forming the upper bearing for the target staff 9. The other staff bearing is formed in the floor of the chamber and consists of an annular boss 10, projecting somewhat above the chamber floor, and a step-piece 11, which

projects upwardly from the bottom of the recess within the boss, these parts being arranged so as to provide ample clearance around the step-piece 11, as shown in Figs. 60 6 and 7. Both staff bearings are, of course, formed in alinement with each other and may be easily formed in the casting, to be then reamed out and finished by a single operation with a reamer. The crank arm 65 12 is secured to the staff 9, between its bearings in the roof and floor of the chamber, and is preferably threaded crosswise through a hole in the staff, so that its effective length can be varied, and its inner or 70 fulcrum end will normally project more or less into the interior of the chamber, while its opposite or connection end will extend outside of the chamber and beyond the base casting where it is connected with the connecting rod in the usual manner. In the present case the crank-arm is an eye-bolt, and after it has been adjusted, is held 75 against displacement by the hooked end of the connecting rod, which is pinned to its 80 eye. A sleeve 13 surrounds the target staff between its bearings, and the crank arm 12 passes through the sleeve as well as the staff, so that when these parts are assembled, the staff cannot be unstepped without 85 first removing the eye-bolt. Manifestly the penetration of the eye-bolt in or through the staff serves as the primary locking agency, the sleeve 13 being merely a filler 90 to occupy such space in the chamber opening as is not occupied by the staff and eye-bolt. While this form of adjustable connection between crank arm and staff is preferred because of its obvious simplicity and effectiveness, nevertheless it is to be understood that other forms of connection might 95 be employed to accomplish the same purpose. The staff bearings are formed at one side of the chamber and directly above and below the lateral opening therein, so that 100 the parts constituting the junction between staff and crank substantially fill and close such aperture against the entrance of foreign matter. The upright wall portion 6 is desirably continuous, with no openings 105 therein, so that foreign objects, such as pieces of ballast, coal, or the like, cannot obstruct the free movement of the inwardly projecting or fulcrum end of the crank 12, and also so that rain and snow are excluded. 110 The pointed shape of the base casting tends also to prevent obstruction to the operation

- of the stand, since thereby ample clearance is provided for the eye of the crank. The roof of the chamber is desirably dome-shaped, so as to shed water, but is cast with
- 5 5 an interior enlargement or counterbore ^{8a}, so that the whole thickness of the dome-shaped portion will not be required to be reamed to form the staff bearing, and the interior of the chamber is provided with four
- 10 drainage holes 14, located between the ribs 4, to drain away such water as may run down the staff through the upper bearing. The annular clearance space in the step-bearing in the floor of the chamber is likewise provided with drainage holes 15, for the same purpose, but the elevation of the boss 10 and the protection afforded thereto by the sleeve 13, ordinarily prevent the entrance of water to the interior of the step.
- 15 20 Above the base, the target staff carries the usual target 16, and the fitting 17, for a signal lamp.
- I claim:
1. A target stand comprising a base having an upstanding portion forming a closed, water-shedding chamber with a lateral opening therein, in combination with a target staff supported by the upper and lower portions of such chamber and substantially closing the lateral opening.
  2. A target stand comprising a base plate having an upstanding integral wall portion forming a chamber with a lateral opening, in combination with a target staff stepped in the floor of the chamber and journaled also in the roof thereof, and a crank arm on the said staff, the crank arm portion of said staff substantially closing the aforesaid lateral opening.
  3. A target stand comprising a base having an integral wall portion forming a chamber adjacent to the edge of the base and said chamber having a lateral opening, in combination with a staff journaled in the roof and floor of the chamber and having a crank arm, the junction of arm and staff substantially closing the said lateral opening.
  4. A target stand comprising a base having an upstanding wall portion forming a chamber normally closed at the top and sides but having a lateral opening, a staff journaled in the roof and floor of the chamber, a crank arm on the staff adjustable crosswise thereof, the junction portions of crank and shaft being arranged to close the said lateral opening with the inner end of the arm inclosed within the chamber.
  5. A target stand comprising a substantially fan-shaped base plate having spike holes along its wider side and an integral wall portion forming a normally closed chamber at its pointed end, a lateral opening in the outer side of the chamber wall, a staff journaled in the roof and floor of the
- chamber, and a crank thereon extended away from the chamber, the junction of the crank and staff serving as a closure to the lateral opening.
6. In a target stand, the combination of an upright staff, a crank arm thereon adapted for adjustment crosswise of the staff, whereby its fulcrum end may extend in rear of the staff, a base plate providing bearings for such staff above and below the crank arm and also providing a protecting and inclosing chamber for the said extended fulcrum end of the crank arm.
7. In a target stand, the combination with a base having spike holes along one edge and having an upright portion providing a chamber at its opposite edge, a staff journaled in the roof and floor of the chamber, a crank arm having one end projecting adjustably through the staff and adapted to swing within the chamber, and its other end projecting beyond the chamber and base plate, and provided with connection means.
8. A target stand comprising a substantially fan-shaped base-plate with upright wall portions forming a chamber adjacent to the smaller end of the base-plate, a target staff stepped in the floor and journaled in the roof of the chamber, a sleeve surrounding the target staff between its bearings, and a crank arm having one end extending beyond the sleeve and staff into the interior of the said chamber.
9. A target stand comprising a substantially fan-shaped base having spike-holes along its longer side and an upstanding wall portion forming a protecting chamber at smaller end thereof, a water-shedding roof for said chamber, a target staff journaled in the roof and stepped in the floor of the chamber and an eye-bolt crank arm threaded to the shaft between its bearings, the eye of the crank arm being without the chamber and its opposite end within the chamber.
10. In a target stand, the combination of a base-plate with upright wall portions at one end thereof forming a protecting chamber, a target staff and bearings therefor comprising an aperture in the roof of the chamber, a recess in the floor thereof and an elevated step at the bottom of the recess, a crank arm threaded crosswise in the shaft between the bearings, one end of said arm being within the chamber and the other projecting to the exterior thereof and overhanging the base plate.
11. A target stand comprising a base plate with upright wall portions forming a chamber with a water-shedding roof and a lateral opening, a bearing aperture in the roof of the chamber, a staff journaled therein, an adjustable crank arm on the staff, the junction portion of arm and staff serving to close said lateral opening, a step-bearing in the floor of the chamber having

its entrance elevated above said floor, and drainage holes in the floor of the chamber.

12. A target stand having a base provided with a portion having spike holes, the remaining portion thereof having convergent sides with an upright wall portion at the pointed end thereof, a target staff, the upper bearing for the same, formed in said upright wall portion, a step bearing therefor in the base proper, and a crank arm secured to the staff between said bearings and projecting beyond the convergent sides of the base.

13. In a target stand, a base plate with spike holes formed therein along one side thereof and an upright wall portion at the

opposite side, provided with journal bearings, and a series of ribs formed in the base plate above and below the general plane of the same and convergently disposed from 20 the margin containing the spike holes toward the axis of said bearings and serving to brace the upright wall portion of the base plate.

In testimony whereof, I have signed this 25 specification in the presence of two witnesses.

STANLEY W. HAYES.
